UNITED STATES PATENT OFFICE.

BENJAMIN G. VAN DYKE, JR., OF DETROIT, MICHIGAN.

RAILWAY-TRACK CROSSING.

1,354,080.

Specification of Letters Patent. Patented Sept. 28, 1920.

Application filed September 13, 1919. Serial No. 323,527.

To all whom it may concern:

Be it known that I, BENJAMIN G. VAN DYKE, Jr., a citizen of the United States, and a resident of Detroit, in the county of Wayne and State of Michigan, have made certain new and useful Improvements in Railway-Track Crossings, of which the following is a specification.

My invention relates to railway track crossings, and an object of my invention is the provision of a crossing comprised of movable rail sections which are capable of occupying one extreme position in which they provide gaps to form a clearance for the wheel-flanges of a car, and another extreme position in which they provide an unbroken rail surface for the passage of a wheel thereover without the incident jars and bumps which occur in crossings of the ordinary construction.

It is also an object of my invention to provide simple and efficient means for actuating the rail sections, and for securely locking the same in active position.

I will describe one form of railway track crossing embodying my invention, and will then point out the novel features thereof in claims.

In the accompanying drawings:

Figure 1 is a view showing in top plan one form of track crossing embodying my invention in which two pairs of intersecting tracks are shown.

Fig. 2 is an enlarged fragmentary view showing a portion of the crossing shown in Fig. 1.

Fig. 3 is a sectional view taken on line 3—3 of Fig. 2.

Fig. 4 is a sectional view taken on line 4—4 of Fig. 2.

Figs. 5, 6 and 7 are detail views of different parts of the crossing shown in Figs. 1 and 2.

Fig. 8 is an enlarged detail view of one of the sets of track sections.

Similar reference characters refer to similar parts in each of the several views.

Referring specifically to the drawings and particularly to Fig. 1, I have here shown a track crossing comprising double tracks T, intersected by double tracks T', the rails R and R' of adjacent intersecting tracks being supported by rectangular plates P secured to frames F of corresponding contour by means of bolts 16. The rails R and R' supported upon each plate

P comprise stationary rail sections S and movable rail sections S', S² and S³. As illustrated to advantage in Figs. 2 and 6 all of the rail sections are held in position upon plate P by means of bars B which are secured in pairs to the plate by bolts 17. As shown in Fig. 6 the underside of the bars B are curved in such a manner that each pair co-act with the plate P to provide a T-shaped slot for receiving the base of the rails R and R'. The size of the slot provided by the bars B is such that the rails have a sliding fit therein. However, the rail sections S are locked against movement within the bars B by means of angle plates 18 which are secured at the intersection of adjacent rails, as clearly shown in Fig. 2. The movable rails S' and S² are free to slide longitudinally between the bars B for a purpose which will be hereinafter described.

The movable rail sections S' and S² have their confronting ends beveled or inclined in opposite directions as at 19 while the opposite ends of the rail section S³ are also beveled or inclined in opposite directions as at 20. The section S³ is mounted for lateral movement with respect to rail sections S' and S², and to this end I provide angle bars 21 which are secured to the plate P in a manner to provide a T-shaped slot to slidably receive a shank 22 extending laterally from one side of the section S³. The shank 22 is operatively connected to the respective sections S' and S² by means of bell crank levers 23 and 24 and links 25 and 26. As shown in Fig. 8, the bell crank levers are pivotally connected at one end to the shank 22 while the opposite ends are pivotally connected to one end of the links 25 and 26. At the junction of the arms of each bell crank lever, each lever is fulcrumed as at 27 to swing about this point as a center.

From this arrangement it will be seen that when the section S³ is moved between the sections S² and S' from the position shown in Fig. 8, the levers 23 and 24 and links 25 and 26 will move the sections S' and S² longitudinally in opposite directions so as to provide ample space between the confronting ends thereof to receive the section S³. It will be understood that when the section S³ is moving into position between the sections S' and S² the surfaces 19 and 20 contact with each other and as-

100

110

sist in moving the sections S' and S^2 apart. When the section S^3 is retracted from between the sections S' and S^2 , it is obvious that because of the bell crank levers, the sections S' and S^2 will again occupy the position shown in Fig. 2.

From the foregoing operation, it will be manifest that the sections S' and S^2 are capable of occupying two extreme positions, 10 one in which the outer ends are spaced from the sides of adjacent intersecting rails, which position I term the inactive position, and another extreme position in which the outer ends lie contiguous to the ends of adjacent stationary rail sections S , and which 15 position I term the active position. When the sections S' and S^2 are in the active position, a substantially uninterrupted surface is provided on a rail for allowing the 20 uninterrupted passage of a wheel thereover, and thereby eliminating the bumps and jars to which they are usually subjected when crossing intersecting rails. With the rail sections S' and S^2 in inactive position, gaps 25 between the confronting ends of adjacent stationary and movable rail sections are provided to form the necessary clearance for the wheel flanges of a car traversing the rails of the intersecting tracks.

30 In order that the several sets of movable rail sections may be operated to active and inactive positions according as the train or car is traversing one track or the other, I provide an operating mechanism which I 35 will now describe, although, it is to be understood that any suitable mechanism may be provided to accomplish the same end without departing from the spirit and scope of my invention.

40 As shown in Fig. 1, the shanks 22 of the two track sections S^3 of any one rail R or R' are pivotally connected as at 28 to the opposite ends of a beam 29, which extends through suitable openings formed in the 45 rails. Each beam 29 is adapted to be moved laterally in one direction or the other to move the movable rail sections into active or inactive positions according as it occupies one position or the other. From this 50 operation, it will be seen that the beams 29 for actuating the movable track sections of the rails of any one track are adapted to be moved in opposite directions with respect to each other in order to move the rail sections from one extreme position to the other. For example, the beams 29 of the upper track T' Fig. 1 are now in active position, that is, a position in which the movable rail sections assume active positions, and when 55 it is desired to move these rail sections to inactive position to allow for the passage of a car over the rails of the tracks T , the beams 29 are moved away from the adjacent rails R and R' of the track T' .

60 65 In order to actuate each pair of beams 29

to effect a movement of the rail sections to active or inactive position according as the car is traversing the tracks T or T' , I provide a shaft 30 which is formed at one of its ends with arms 31 and 32 connected to 70 sectional rods H and H' respectively, as is clearly shown in Fig. 3. The rod H is pivotally connected to the intermediate portion of the beams 29^a and 29^b while, the rod H' is connected to the beams 29^c and 29^d. 75 The shaft 30 is adapted to be partially rotated in one direction or the other from an intermediate position by means of a lever 33, which as shown in Fig. 7 carries a pawl 80 34 and actuating means therefor for moving the same into and out of engagement with a rack 35. The rack 35 is supported independently of the shaft 30 while the lever 33 is rigidly connected thereto and is adapted to be locked in any adjusted position by means 85 of the pawl 34 engaging the rack 35.

As shown in Fig. 1, the several sets of movable rail sections which are actuated by the beams 29^a to 29^d inclusive, are in inactive position. When it is desired to move all of 90 these sections into active position, the shaft 30 is rocked by the lever 33 to move the rod H to the right and the rod H' to the left as when viewed in Fig. 3. During this movement, the beams 29^a and 29^b are moved to 95 the right, as viewed in Fig. 1 causing the rail sections to occupy active position, while the beams 29^c and 29^d carried by the rod H' have been moved in the opposite direction to move their respective rail sections 100 into active position. It will be understood that when the shaft 33 is rocked in the opposite direction, the rods H and H' will be actuated to cause their respective rail sections to occupy inactive positions. From 105 this arrangement it will be seen that when the rail sections occupy one extreme position or the other the movable rail sections S' and S^2 of all the rails of tracks T will be moved to active or inactive positions. 110

The mechanism for actuating the beams for the movable rail sections of the tracks T' is identical to the mechanism just described in so far as the rods H and H' are concerned. However, the rods H and H' 1 are actuated by means of a shaft 30^a which is connected to the rods H and H' intermediate their ends. The shaft 30^a is adapted to be actuated by means of a rod H^2 which 15 is connected to one end of the shaft by an arm 36, as shown in Fig. 4. The opposite end of the shaft 30^a is connected to an arm 37 (Fig. 1) formed on a stub axle 38. The axle 38 carries a lever 33^a which can be locked in any position by means of a pawl 1 and ratchet, as has been described in connection with the lever 33. By means of this arrangement the shaft 30^a can be oscillated by the movement of the lever 33^a to move the rods H and H' to one extreme 1

position or the other and thereby effect the movement of the movable rail sections for the rails or tracks T' to active or inactive position.

tion for each pair of sections, all the third
movable sections being disposed upon outer
sides of said rails and adapted to be inter-
posed between the pair of movable sections
when the latter are in active position, and
withdrawn from the same when they are in
inactive position, and mechanism arranged
upon the outer sides of said rails for mov-
ing all of the movable sections of the rails
of one pair of tracks into active or inactive
position, said means comprising beams dis-
posed upon the outer sides of the rails and
parallel thereto, the beams for each track
being movable laterally in opposite direc-
tions, and levers operatively connecting said
beams and sections, pairs of superposed rods
mounted for reciprocating movement and
connected to said beams, and oscillatory
means for actuating the rods of each pair
in opposite directions.

3. In combination, a pair of track rails comprising movable sections and stationary sections, said movable sections being arranged in pairs and movable longitudinally of the rails and capable of occupying active and inactive positions, a third movable section for each pair of sections, all the third movable sections being disposed upon the outer sides of said rails and adapted to be interposed between a pair of movable sections when the latter are in active position, and withdrawn from the same when they are in inactive position, and mechanism arranged upon the outer sides of said rails for moving all of the movable sections of one rail or the other into active or inactive position, said means comprising beams disposed upon the outer sides of the rails and parallel thereto and movable in opposite directions, levers operatively connecting said beams and sections, and superposed rods mounted for reciprocating movement and connected to said beams. 85

BENJAMIN G. VAN DYKE, JR.
